(57) **CLAIM**

The ornamental design for a clock sign, as shown and described.

DESCRIPTION

FIG. 1 is a perspective view of the clock sign showing my new design;

FIG. 2 is a top plan view of clock sign showing my new design;

FIG. 3 is a bottom plan view of the clock sign of FIG. 1; FIG. 4 is a side elevational view of the clock sign of FIG. 1; FIG. 5 is a opposite side elevational view of the clock sign of FIG. 1;

FIG. 6 is a rear elevational view of the clock sign of FIG. 1; and,

FIG. 7 is a front elevational view of the clock sign of FIG. 1.

In the drawings, the broken lines are for illustrative purposes only and form no part of the claimed design.
